UNITED STATES PATENT OFFICE

2,349,657

TUBULAR FILM EVAPORATING APPARATUS

Carl Maximilian Axel Hermelin, Ulvsunda, Stockholm, Sweden, assignor to Aktiebolaget Rosenblads Patents, Stockholm, Sweden

Application October 25, 1940, Serial No. 362,761
In Sweden October 26, 1939

4 Claims. (Cl. 159—13)

The invention refers to tubular film evaporating apparatus and more particularly to such apparatus of the type which comprises a plurality of vertical heating tubes arranged within a common evaporating chamber so as to receive the liquid to be evaporated in the form of a film on their outer surfaces, while being heated by any suitable heating medium which is introduced into the tubes.

It is an object of the invention to so arrange the heating tubes in apparatus of the character described that they are freely expandable at their upper ends in the axial direction, in order to eliminate undue stresses on account of varying temperature conditions.

Another object of the invention is to provide means for radially guiding the heating tubes at the upper tube ends so that they are kept in the correct vertical position without axial expansion being prevented.

Still another object of the invention is to provide liquid distributing means for feeding the liquid to be evaporated onto the outer surfaces of the heating tubes at the upper ends of the latter so as to cause the liquid to flow down over the tubes in a proper film formation, and constructing the liquid distributing means so that they may also serve as guiding means for the upper ends of the tubes.

A further object of the invention is to prevent the upper end portions of the heating tubes, which first receive the liquid, from being heated by the heating medium in order to prevent scale formation which would interfere with the formation of the liquid film.

Various further objects of the invention will be apparent from the following description describing more in detail an embodiment of the invention and some modifications of certain features thereof, as shown in the accompanying drawing of which:

Fig. 1 is a vertical section through an evaporating apparatus according to the invention;

Fig. 2 is a vertical section through certain portions of such apparatus, illustrating on an enlarged scale the upper end of a heating tube with combined liquid distributing and guiding means for the same, all of a similar design as in Fig. 1;

Fig. 3 is a vertical section through the corresponding parts of another embodiment thereof;

Fig. 4 is top view of the embodiment shown in Fig. 3; and

Figs. 5 and 6 are vertical and cross sectional views, respectively, the latter taken on line 6—6 in the former, of a still further modification.

Referring now to Fig. 1 of the drawing, the evaporating apparatus as here shown includes a substantially cylindrical vertically disposed casing, consisting of three joined parts of which the central one, designated by reference character 1 forms an evaporating chamber. The evaporating chamber is separated by horizontal plates 2 and 3, respectively, from an upper and a lower chamber formed by the parts 1a and 1b of the casing and their end covers. The liquid which is to be evaporated is supplied to the upper chamber through the inlet 4 and removed from the evaporating chamber through the outlet 5, while the vapours generated therein escape through the outlet 6. To the lower chamber there is supplied a heating medium, preferably steam, through the inlet 7 and the condensate is discharged therefrom, through the outlet 8.

In the evaporating chamber there are inserted 20 a plurality of heating tubes 10 which at their lower ends are fixed to the lower plate 3 and communicate therethrough with the lower chamber so that the heating medium has access to the interior of the heating tubes. The upper ends of 25 the heating tubes 10 terminate somewhat below the upper plate 2 and are closed by means of end pieces 11 whereby there is defined a separate top space within the end portion of each tube, said top space being partitioned from the tube channel proper, while being open upwards. Further, the upper plate 2 is designed to serve as 30 liquid distributing means and for that purpose it is provided with small supply pipes 12 or the like, each of which is arranged to project downwards in coaxial relationship with a corresponding heating tube and into the top space of the same so as to feed liquid into that top space.

A similar arrangement of liquid distributing means is more clearly shown in Fig. 2, wherein 2a 40 indicates the upper plate of the evaporating chamber and 12a one supply pipe of said plate for the heating tube 10 which has a somewhat modified end piece 11a in the form of a cylinder with one end closed, being fitted into the heating tube with the closed end forming an inside partition and welded to the former at the juxtaposed free terminal edges of both. The supply pipe 12a, which projects into the separate top space of the heating tube, as formed by the end piece 11a, has disposed within the latter radially outwards extending wing-like guiding means 13a, the outer vertical edges of which approximately coincide with the vertical inner surface of said top space 45 so that the heating tube is kept in the correct

vertical position without preventing axial expansion of the otherwise entirely free upper end.

Since the top space of the heating tubes 10 will be filled with liquid and any evaporation therein should be avoided, as this might result in scale formation which would be apt to obstruct the supply of liquid, it is most advisable to provide means for preventing heat transmission to said space from the heating medium in the heating tube. For this purpose either the walls of the top space referred to may be insulated by a layer of some suitable non-heat-conducting material, at least at the bottom, as indicated at 111 in Fig. 1, or as shown in Fig. 2, there may be inserted an additional partition wall 14 in the heating tube a short distance beneath the upper end piece 11a so as to form an insulating space under the same.

The evaporating apparatus described works substantially as follows: The liquid which is to be evaporated enters through the inlet 4 into the upper chamber of the apparatus where it will stand therein to a certain level over the plate 2. From here it is delivered by the pipes 12 into the top space of the corresponding heating tubes 10 and then caused to flow over the upper edges thereof so that it will pass downwards along the outside tube surfaces in the form of a film. Finally, any position of liquid remaining unevaporated at the lower ends of the heating tubes is collected at the bottom of the evaporating chamber above the plate 3 and is withdrawn therefrom through the outlet 5. During the passage of the liquid alone the heating tubes, evaporation takes place due to heat transfer through the tube walls from the heating medium supplied to the tube channels through the inlet 7 to the lower chamber. The vapours thus generated escape from the evaporating chamber through the outlet 6.

It is an important advantage of this type of apparatus that the vapours are readily separated from the liquid, practically at the same place and moment as generated and therefore over the greatest possible surface while at a relatively low velocity, so that normally no inadmissible great quantity of liquid will be carried away by the vapours which would require additional separating means.

According to Fig. 3 the liquid distributing and guiding means for the heating tubes 10 can be replaced by a plate 2b with supply openings 12b which are suitably circular in cross section and located directly above the respective heating tubes. In this case the end piece 11b of the heating tubes is made plug-like, as here shown, or possibly cap-like in shape and is removably attached to the upper tube end so as to close the same. The end piece 11b should preferably form an outward conical cover for the tube terminal, and is provided with a centrally disposed rod-like member 25 which projects vertically upwards. This rod-like member, which is coaxial with the heating tube, fits into the corresponding supply opening 12b of the plate 2b but has such a cross section, cross-shaped, for instance, that it engages only comparatively small portions of the periphery of the opening. Moreover, the arrangement is such that a sufficient area of the opening is left unobstructed for the passage of liquid which will thus be spread over the end piece of the heating tube and caused to flow down over the outside tube surface in film formation. By virtue of this arrangement the heating tube 10 is free to expand and contract in axial direc-

tion while being kept in the correct vertical position by the rod-like member of the end piece 11b which is guided in the opening 12b.

As shown by Figs. 5 and 6 a further possible modification of the liquid distributing and guiding means for the heating tubes consist in having the heating tubes 10, which in this case have the upper ends closed by an end piece 11c welded to the terminal edges of the tube, arranged to project through corresponding supply openings 12c in the plate 2c. The diameter of the openings 12c is somewhat greater than that of the heating tube so that an annular slot for the passage of the liquid is formed around the same, and thus the liquid is caused to flow down over the outside tube surface in film formation, but at some points, however, the periphery of the opening provides guiding surfaces for the heating tube 10 in the form of small radial projections 13c adapted to engage the tube surface so that the tube is kept in the correct vertical position, while being free to expand and contract vertically.

Naturally a great many other changes fall within the scope of the invention and it is understood that the invention is not limited otherwise than by the appended claims.

Thus, what I claim as new and desire to secure by Letters Patent is:

1. In an evaporating apparatus, a tubular member providing an exterior evaporating surface, means rigidly secured to the lower part of said member for supporting it in a vertical position, means for introducing a heating medium into the lower end of said member, an end wall disposed in said tubular member a short distance below its upper end to thereby provide a space within the upper end open at the top, a rigidly supported liquid supply pipe terminating in said space, the outer diameter of said pipe being less than the inner diameter of said space, and rib-like members extending radially from said pipe and slidably engaging the inner sides of said space to maintain said tubular member in a vertical position while permitting vertical expansion and contraction thereof.

2. In an evaporating apparatus, a tubular member providing an exterior evaporating surface, means rigidly secured to the lower part of said member for supporting it in a vertical position, means for introducing a heating medium into the lower end of said member, a liquid distributing plate disposed above said tubular member and having an opening in alignment with the axis of the member, an end piece for closing the upper end of said tubular member, and a rod-like member extending upwardly from said end piece and into said opening, the cross-sectional configurations of said rod-like member and said opening being such that the former slidably contacts the side of the latter at spaced points to maintain said tubular member in a vertical position while permitting expansion and contraction thereof, and is spaced from the side of said opening at other points to provide for flow of liquid therethrough.

3. In an evaporating apparatus, a substantially horizontal liquid distributing plate member formed with an opening therethrough, a tubular member providing an exterior evaporating surface, means for closing the upper end of said tubular member, means rigidly secured to the lower part of said tubular member for supporting it in a vertical position with the closed upper end thereof directly below said opening, means for introducing a heating medium into the lower end

of said tubular member, and an outwardly flanged rigid element associated with the upper end of said tubular member and extending into said opening for guiding liquid flowing through said opening to the exterior of said tubular member, said rigid element being fixed to one of said members and the flanges thereof being in vertically slidable contact with the other of said members to thereby maintain the upper end of said tubular member in alignment with the opening in said plate member while permitting vertical expansion and contraction of said tubular member with respect to said plate member and permitting flow of fluid between the exterior of said element and said other of said members.

4. In an evaporating apparatus, a substantially horizontal liquid distributing plate member formed with an opening therethrough, a tubular member providing an exterior evaporating surface, means rigidly secured to the lower part of said tubular member for supporting it in a vertical position directly below said opening, means

for introducing a heating medium into the lower end of said tubular member, means for closing said tubular member a short distance below its upper end whereby the heating medium is prevented from flowing to the extreme upper end of the tubular member, and an outwardly flanged rigid element associated with the upper end of said tubular member and extending into said opening for guiding liquid flowing through said opening to the exterior of said tubular member, said rigid element being fixed to one of said members and the flanges thereof being in vertically slidable contact with the other of said members to thereby maintain the upper end of said tubular member in alignment with the opening in said plate member while permitting vertical expansion and contraction of said tubular member with respect to said plate member while permitting flow of fluid between the exterior of said element and said other of said members.

CARL MAXIMILIAN AXEL HERMELIN.
